[57] CLAIM

The ornamental design for a safety step for attachment to a truck tailgate, as shown and described.

DESCRIPTION

FIG. 1 is a front elevation view of a safety step for attachment to a truck tailgate showing my new design, it being understood that the rear is substantially a mirror image thereof;

FIG. 2 is a top plan view thereof, it being understood that the bottom is flat and unornamented;

FIG. 3 is a side elevation view thereof, the opposite side being a mirror image of that shown; and,

FIG. 4 is an enlarged fragmentary cross sectional view thereof taken along line 4—4 in FIG. 1.

FIG. 1

FIG. 2

FIG. 4

FIG. 3
